(57) CLAIM

The ornamental design for a customizable watch, as shown and described.

DESCRIPTION

FIG. 1 is a 3 dimension view of a customizable watch showing my new design;

FIG. 2 is a front view thereof;

FIG. 3 is a rear view thereof; and,

FIG. 4 is a right side elevational view thereof, the left side being a mirror image thereto.

The broken line showings of other segments are for illustrative purposes only and form no part of the claimed design.
